UNITED STATES PATENT OFFICE

HARVEY L. GLIDDEN, OF LEXINGTON, MASSACHUSETTS, ASSIGNOR TO UNITED SHOE MACHINERY CORPORATION, OF PATERSON, NEW JERSEY, A CORPORATION OF NEW JERSEY

TAG HOLDER

Application filed May 22, 1929. Serial No. 365,073.

This invention relates to tag holders and is herein illustrated as embodied in a shoe rack.

In shoe factories it is common practice to make use of racks provided with shoe-supporting members for holding shoes between operations performed upon the shoes and for carrying them from one place of operation to another. Shoes in process and, consequently, the racks upon which they are carried are routed through the factory in such manner that operations can be performed upon the shoes in a predetermined order. To assist in maintaining this order various types of work tags or tickets have been adopted. These tags, which are commonly eighteen inches or more in length, bear at the top the information required by the operators properly to perform the various operations upon the shoes. In addition, the tags usually contain a complete list of the operations to be performed upon the shoes from the time the lasts are picked until the shoes are treed. Such tags or tickets accompany each unit lot of shoes—six, twelve or twenty-four pairs as the case may be—and accompany the racks carrying the shoes. After an operator performs an operation upon a lot of shoes he cuts from the tag that portion thereof which bears the indicia of the operation which he has performed. The portion referred to constitutes a check upon or evidence of the fact that the operator has performed the required operation and forms the basis upon which the operator's pay is determined.

It has heretofore been common practice to attach such tags to shoe racks by placing them upon nails, or hooks, or other holding devices set in the frames of the racks. In this connection considerable difficulty has been experienced because of the fact that the tags are handled by a number of persons, frequently as many as forty, before the shoes are finished, with the result that repeated handling of the tags very often renders them torn or otherwise mutilated to the extent that it is impossible to keep them on the holding devices, thereby rendering their inspection difficult as well as occasionally causing the

loss of a tag. Further than this, tag-holding devices as heretofore provided for use on shoe racks usually have a shank which is driven or screw-threaded into a portion of the frame of the rack. An objection to such manner of securing a tag-holding device is that the workmen in moving racks from one place to another commonly grasp the holding device by the shank and bend it out of position, break it, or so loosen it in its socket that it is no longer effective for holding tags. 55

In view of the foregoing, an object of the present invention is to provide an improved tag holder which, while retaining the advantages of tag holders heretofore used, will be of rugged construction, will render less likely mutilation of tags carried by the holder, and at the same time will make it possible for an operator readily to inspect the tag. To this end and as illustrated one feature of the invention consists in the provision of a novel tag holder comprising a standard having tag-supporting means so constructed and arranged that a tag carried by the device can be moved into a position where it can be readily inspected. 70 75

Preferably, the tag-supporting means extends laterally from the upper end of the standard and is herein shown as an eye by which the tag is loosely carried so that it can be moved laterally for purposes of inspection without creasing or bending the tag to such an extent that it is likely to be torn. Furthermore, by supporting tags in the manner set forth the standard does not project a great distance above the surface of its support, for example the upper surface of the frame of a shoe rack, with the result that it cannot be readily displaced. As illustrated, the standard is held in position by means of a sleeve having tapered portions which engage portions of the standard to retain it in the sleeve with the tag-supporting portion at a predetermined distance above the surface of its support. This construction permits turning of the standard in the sleeve, thus further minimizing likelihood of bending the standard or loosening it, while at the same time it provides for the location of the tag- 80 85 90 95 100

2 supporting portion in various positions angularly to facilitate inspection of the tag.

These and other features of the invention will be understood from the following description when taken in connection with the accompanying drawings, in which,

Fig. 1 is a perspective view of a portion of a shoe rack embodying the invention;

Fig. 2 is a detailed view partially in section, showing the tag holder in position; and

Fig. 3 is a perspective view of the tag holder with the parts separated.

Fig. 1 illustrates a portion of a shoe rack comprising frame members 10 and a plurality of shoe-supporting shelves 12. Secured to the upper portions of the frame members 10 is a hand-rail 14 which serves as a support for a tag holder indicated generally by reference character 16.

As shown in Figs. 2 and 3, this tag holder comprises a hook 18 loosely carried by a vertical standard 20 which is positioned in a slot 22 in the hand-rail 14. The standard 20, which is formed from a comparatively heavy metal rod, has at its upper end a laterally extending eye 24 through which is passed a loop 26 forming the upper portion of the hook 18. The arrangement of parts just described is such that the hook 18 is so carried by the eye 24 that it is practically universally mounted with the result that a tag or ticket carried upon the hook can be turned in any direction for inspection purposes without the necessity of removing the tag from the hook and without any likelihood of tearing the tag. Preferably the lateral extent of the eye 24 relatively to the width of the hand-rail 14 is such that, when in the position shown in Figs. 1 and 2, the body portion of the hook 18 extends beyond the hand-rail 14 so that a tag carried by the hook will hang clear of the rack. It should be noted that the hook 18 is turned inwardly toward the standard 20 thereby to lessen the possibility of pulling the tag off the hook if the hole in the tag is large and to avoid the danger of catching the clothes of the operator.

As shown, the standard 20 is positioned in the hand-rail 14 by means of a split sleeve 28 of spring metal driven into the slot 22. The sleeve 28 has tapered end portions 30 which engage with a flattened projecting portion 32 of the standard 20 to support the standard with the eye 24 spaced by a predetermined distance from the upper surface of the hand-rail 14, but at the same time to permit rotation of the standard about its vertical axis. The end of the standard is provided with a flattened projecting portion 34 of such width that it can be forced past the end portions 30 of the spring sleeve 28 upon insertion of the standard in the sleeve but which will operate to prevent easy withdrawal of the standard from the sleeve. This construction is advantageous in that it provides a rugged sup-

port for the hook 18 which will maintain the hook in the position desired in spite of the rough usage to which shoe racks are subjected.

In the use of the device a tag or ticket is placed upon the hook 18 with the printed side of the tag facing outwardly. When an operator desires to inspect the tag he grasps it and turns it toward him, the hook 18 sliding laterally along the eye 24, thus making it possible for the operator readily to inspect the tag from a position at either side or the end of the rack.

Having described the invention, what I claim as new and desire to secure by Letters Patent of the United States is:

1. A tag holder comprising a spring sleeve having a tapered end portion, and a standard positioned in the sleeve and having a projection for co-operating with the tapered end portion of the sleeve for retaining the standard in position.

2. A tag holder comprising a tapered sleeve, a standard positioned in the sleeve and having at one end tag-supporting means, and a projection upon the standard for engaging the sleeve to hold the standard with the tag-supporting means in predetermined position heightwise of the sleeve.

3. A tag holder comprising a sleeve having a tapered end portion, a standard one end of which is rotatably mounted in the sleeve and having at its other end a laterally extending eye, a projection on the standard co-operable with the tapered portion of the sleeve normally to retain the eye in predetermined position heightwise of the sleeve, and a second projection on the standard co-operable with the end portion of the sleeve for retaining the standard in the sleeve.

In testimony whereof I have signed my name to this specification.

HARVEY L. GLIDDEN.
